UNITED STATES PATENT OFFICE.

JOHN EVANS, JR., AND JAMES EVANS, OF SALT LAKE CITY, UTAH.

BELT-FASTENER.

1,087,777.

Specification of Letters Patent.

Patented Feb. 17, 1914.

Application filed February 1, 1912. Serial No. 674,657.

To all whom it may concern:

Be it known that we, JOHN EVANS, Jr., and JAMES EVANS, both citizens of the United States, and residents of Salt Lake City, in the county of Salt Lake and State of Utah, have invented a new and Improved Belt-Fastener, of which the following is a full, clear, and exact description.

The invention relates to belt fasteners of the type in which a plate is provided with spaced fingers comprising, in general, the form of a comb plate, the fingers being designed to be passed through holes adjacent to the meeting ends of the belt, the free ends 15 of the fingers having means for preventing their accidental withdrawal.

It is the usual practice to produce round holes in the belt by suitable punches or the like, and it is a prime desideratum that the 20 holes be of such a character as to leave the maximum of material between the holes, so that the belt may not be materially weakened at this point; and a further desideratum is to provide a fastening means that will 25 minimize the strain on that portion of the belt material between the holes.

An object of our invention is to provide a comb plate, and fingers so disposed relatively to each other that the plate will bear 30 flatwise against the belt adjacent to and in the rear of the belt holes so as to relieve the material of the belt between the holes from the wearing action of the plate. Another object is to give the free ends of the fingers 35 such a formation as to permit them to be threaded through a small belt hole approximating in diameter the thickness of the fingers, so as to leave the maximum amount of material in the belt between the holes.

Further objects will appear from the more 40 specific description hereinafter to be given in connection with the particular example given as a practical embodiment of our invention.

Reference is to be had to the accompanying 45 drawings forming a part of this specification, in which similar characters of reference indicate corresponding parts in all the views.

Figure 1 is a plan view of our improved 50 fastener as applied to a belt; Fig. 2 is a perspective view of the fastener; Fig. 3 is a longitudinal vertical section on the line 3—3 of Fig. 1; and Fig. 4 is a perspective view 55 of the locking and bearing plate that advan-

tageously is employed in connection with the free ends of the fingers.

In forming a belt fastener in accordance with our invention, the fingers 10 project integrally from a plate 11 and the fingers 60 are given a downward bend preferably in curved form, as clearly shown in Figs. 2 and 3, and it will be observed that the fingers emanate from the plate 10 at the base at approximately the normal angle, so that the 65 plate will lie flatwise on the belt end as 12, and present by its under side a broad surface rearward of the belt holes 13. It will thus be observed that the plate 11 by presenting a broad surface exerts a minimum 70 wearing strain, and the wear is practically removed from the portions of the belt between the holes 13. The forward edge of the plate 11 advantageously is provided with additional projecting members 14 that 75 extend a short distance between the fingers, and in practice, overlie the material of the belt between the holes 13, the forward ends of said members 14 terminating on a line beyond the said holes, the effect of which is 80 to increase the pulling surface of the plate 11, and to further lessen the strain on the material between the holes.

The free ends of the fingers 10 are given 85 an outward and downward inclination to the curved body of the fingers, as at 15, and said members 15 are elongated so as to have considerable length, the forward ends being formed with a downward hook 16, which is of a less height than the members 15, the 90 arrangement being such that the fingers may be passed through the belt holes, as 17, in the end 12^a of the belt, the belt holes, being of a diameter only slightly greater than the thickness of the material forming the fastener, said thickness being in practice, at 95 least one eighth of an inch thick to give the required strength to maintain the bent form of the fingers without flexure.

The reason that the fingers can be passed 100 through comparatively small holes is that the hook 16, the portion 15, and the adjacent portion of the body 10 are passed in succession through the holes.

In connection with the free ends of the 105 fingers we provide a separate plate 18, having holes 19 corresponding in number with the fingers, and this plate has such a relation to the fingers as to lie flatwise against the belt both forward and back of the holes 110

17 and present broad surfaces 20 between the holes to overlie the portion of the belt between the holes 17. The plate 18 lies at one edge under the members 15 of the 5 fingers, and that portion of the said plate nearest the meeting edge of the plate overlies the fingers, as clearly shown, the hook member 16 lying against the adjacent edge of the plate 18.

10 By the novel formation of the fingers with the elongated parts 18 and the short hooks 16, the fingers can be threaded through the holes of the belt and those of the bearing plate 18, the members 16 and 15 passing in 15 succession through and over the plate.

Having thus described our invention, we claim as new and desire to secure by Letters Patent:—

20 A belt fastener, comprising two flat plates, one of said plates having curved fingers extending therefrom, and the other plate having holes corresponding in position with the fingers of the first plate and having a transversely arranged flat formation outside 25 said holes to lie flat on the belt, the free ends of the mentioned fingers presenting

two bends forming a flat outward extension, and a terminal, perpendicular, downward bend which forms the terminal of each finger, the said downward bends being of 30 less height than the mentioned flat members, thereby adapting the fingers to be passed through belt holes of a diameter approximately equaling the thickness of the material forming the finger, the downward bends 35 engaging the end edge of the mentioned flat portion of the other plate and terminating in the same plane as the under side of the said other plate, and the plate having the fingers being provided also with flat members between the fingers and at the base of the latter, said members being in the plane of the plate and being spaced from the fingers, at the base of the latter.

In testimony whereof we have signed our 45 names to this specification in the presence of two subscribing witnesses.

JOHN EVANS, JUNIOR.
JAMES EVANS.
